TILE SHAKE

Merle A. Luther, P.O. Box 347,
Cascade, Idaho 83611

Filed June 23, 1972, Ser. No. 265,858

Term of patent 14 years

Int. Cl. D25—01

U.S. Cl. D13—1 J

FIG. 1

FIG. 2

FIG. 3

FIG. 4

FIG. 5

FIG. 6

FIG. 1 is a right front perspective view of a tile shake embodying my new design showing means for interlocking shakes in patterns and designs.

FIG. 2 is an end elevational view of the tile shake of this invention.

FIG. 3 is an end elevational view as seen from the end opposite the FIG. 2.

FIG. 4 is a top plan view of the ornamental design of the tile shake of this invention.

FIG. 5 is a side elevational view of the tile shake.

FIG. 6 is a bottom plan view of the tile shake of this invention as shown from the end opposite the FIG. 4.

I claim:

The ornamental design for a tile shake, substantially as shown.
